UNITED STATES PATENT OFFICE.

FRANK C. WILLIAMS, OF PHILADELPHIA, PENNSYLVANIA, ASSIGNOR TO THE SAFETY BLOCK SIGNAL COMPANY, A CORPORATION OF DELAWARE.

COMBINED TRAIN-STOPPING AND SPEED-CONTROLLING MECHANISM.

Application filed September 22, 1917. Serial No. 192,636.

To all whom it may concern:

Be it known that I, FRANK C. WILLIAMS, a citizen of the United States, and a resident of Philadelphia, in the county of Philadelphia, State of Pennsylvania, have invented certain new and useful Improvements in Combined Train-Stopping and Speed-Controlling Mechanisms, of which the following is a specification.

10 This invention relates to an automatically operating train stopping and speed controlling mechanism whereby a train in a block of a block system will be automatically stopped if there is another train in the block 15 next in advance, while, if the block next in advance is clear but the second block in advance is occupied so that the signal for the train first mentioned is at 45°, then the train will be under the automatic control of the 20 mechanism responsive to the speed of the train so that if the train is proceeding at a moderate rate of speed, say thirty miles an hour for example, the automatic mechanism will not prevent the operation of the train, 25 but if the train is exceeding this rate of speed then the mechanism operates to reduce the speed permitting the same to continue so long as the train remains at the reduced speed.

30 It is therefore the object of this invention to provide a mechanism of this character which shall be automatic in its operation and substantially beyond the control of the operator excepting that there may be provided means whereby under certain conditions, the operator may control the action of the mechanism if the train is then proceeding at a very materially reduced rate of speed. The mechanism which has been provided for accomplishing these ends is one which operates, in so far as any electrical circuits are used, on the closed principle type of circuit so that if any accident occurs to any parts of the mechanism, the apparatus 40 operates to stop the train. Furthermore, it is the object of this invention to include means to insure against accidents should the insulation used as part of the mechanism controlling the electric circuits break down.

In the accompanying drawings illustrating the invention, Figure 1 represents diagrammatically one form of carrying this invention into effect while Fig. 2 represents a 50 modification illustrating diagrammatically

a different form of construction. Fig. 3 also shows a modification.

Referring to Fig. 1, B, C and D represent successive blocks in a block system of a railroad line having track batteries, such as 60 *c* and *d* respectively located in blocks B and C respectively in advance of the blocks C and D, the circuits of the latter being controlled by the batteries located in the blocks in advance thereof as will hereafter more 65 fully appear. At the beginning of each block are also located a signal of the usual semaphore type adapted to indicate "danger," "caution" and "clear" conditions, the "danger" position being designated by 2 70 in block B and the "caution" signal shown at 3 in block C in Fig. 1, while a "clear" signal is represented at 157 in Fig. 3. The signal system is of the usual form whereby upon a train passing into a block, such as 75 block B, the semaphore therefor will immediately indicate "danger," and the operation of the latter will cause the "danger" signal of the succeeding block to change to "caution," as indicated at 3 in block C, and 80 the "caution" signal in block D changed to "clear." Inasmuch as the system is of any approved type, an illustration thereof in this disclosure is deemed unnecessary.

The batteries *c* and *d* are located in the 85 blocks C and D respectively and adjacent the beginning of blocks B and C, respectively as shown, and are connected to insulated sections 11' of the track rails, each battery being normally in a closed circuit 90 including the relay 5 of the succeeding block, as for example, the circuit of battery *c* includes the following: the battery *c*, insulated rail section 11', bond 11, the rail of block C, lead 5'', relay 5, lead 6'', the other 95 rail of block C, the other bond 11, the other insulated rail section 11', back to battery *c*. The other circuits for blocks D and B are similar. It will be observed that the relay 5 is normally energized but when a train 100 enters a block, as for example, block C, the circuit is short circuited, the current passing through the locomotive truck (see truck 64 when advanced into block C) the circuit now being from battery *c* to rail sections 11', 105 bonds 11, rails of block C and the locomotive truck, the relay now being short-circuited and de-energized and the switch 14 open.

Located a certain distance, shown as *x* on the drawings, from the beginning of 116

each of the blocks, is an insulated section 10 in each of the rails of the track, the tracks on each side of these insulated sections being bonded together by wires 11 as shown. 5 These sections are intended to cooperate with the automatic mechanism hereinbelow described to effect the stopping of the train if the signal 2 indicates "danger", or permit the train to be automatically controlled by 10 certain speed responsive mechanism if the signal in a block indicates "caution" or is located at 45° as shown at 3 at the beginning of block C. Any form of train stopping or controlling track located apparatus 15 might be used in my invention but the form I have just referred to, by reason of the insulated sections 10, is well adapted to cooperate with the other elements of my invention as will hereinafter appear to effect 20 the automatic control of the trains intended.

Connected to the wire 11 is a lead 12 passing to a point 13 of the danger switch 14 while a lead 15 connects the same to the caution switch 16, while a lead 17 is connected to a track battery 18, leads 19 and 20 to the insulated section 10, as will be clear 25 from Fig. 1 of the drawing. The caution switch 16 is adapted to cooperate with a point 25 connected to a lead 26 through a resistance 27 and lead 28 to the lead 20. 30 The switches 16 are operated by the movements of their respective signals 2 or 3, or by the electric circuits controlling the said signals, and they are so arranged with respect thereto that the switches 16 are held closed against the contact points 17 except when the signal cooperating therewith is in "caution" position, thus indicating that the next section in advance thereof is in 35 "danger" condition. The simple and obvious way is to provide connections whereby the signals hold their respective switches 16 against the stop 17 at all times except when said signal is in "caution" position. This 40 is for the purpose of making a circuit either through the track battery 18 or the resistance 27, both of which circuits pass through the danger control switch 14 as will appear.

The mechanism carried by the train as a 50 part of my automatic apparatus adapted to cooperate with the track apparatus just described to control the operation of trains in the manner set out above will now be described. A source of air under pressure is 55 provided in the reservoir 30 connected by a pipe 31 to an electromagnet valve 32 and this valve is connected by a pipe 33 to a second electromagnet valve 34. The valve 34 is connected by a pipe 35 to a control chamber 60 36 provided with a valve 37 in the train pipe line 38 which may also be connected by pipe 39 to a cylinder 40 adapted to control the throttle lever 41 of the locomotive. It is apparent, of course, that this mechanism 65 could be used with an electrically propelled

train, in which case, the throttle 41 would be replaced by a switch for controlling the operation of the motors of the train. Interposed between the two valves 32 and 34 and connected to the pipe 33 is a pipe 45 connected to a valve chamber 46 in which a valve 47, adapted to be controlled by the speed of the train, is located, a pipe 48 connects the valve chamber 46 to the pipe 35 and train pipe valve cylinder 36. Located on the pipe 48 is a pressure controlled exhaust valve 50. Any form of speed responsive mechanism for controlling the valve 47 may be provided and I have shown herewith a governor 55, carrying an adjustable arm 56, 80 adapted to engage a rod 57 connected to the valve 47.

The electric circuits for controlling the electromagnet valves 32 and 34 may be of varied construction and, as shown, consists of a battery 60 carried by the train connected by a lead 61 to one side of the magnet 32' while the other side is connected by a lead 63 to ground as by being connected to some un-insulated part of the locomotive 90 illustrated at 64. The truck 65 to which the battery 60 is connected may be insulated from the rest of the locomotive and the train in any suitable manner. The circuit for the other electromagnet valve 34 may be similarly arranged on truck 69 and includes a battery 70 carried by the train and provided with a lead line 71 extending to the magnet 34' while the other side of the magnet 34' is connected by a lead 72 to the ground wire 100 63 above described.

The magnets 32' and 34' are differently constructed so that the magnet 34' requires more current to hold the valve 34 up than does the magnet 32', or, in other words, the 105 resistance due to the magnet 34' is greater than the resistance of the magnet 32'. This is for a purpose of coacting with the track circuits above described in a manner so that under certain conditions the valve 34 will 110 be dropped while the other valve 32 is held open for a purpose as will hereinafter appear to permit the governor control valve 47 to be thrown into operation.

In order to complete the circuit for the 115 magnet 32' under certain conditions, namely, when the train is running at a very slow rate of speed, say, below five miles an hour, there is provided a circuit from battery 60 through line 61 to electromagnet 32' to wire 120 63 and thence through wire 86, switch 85, contact point 84, plate 83, arm 56 to plate 81, to wire 80, to truck 65 and thence to battery 60. The arm 56, located on the governor 55, is provided with an extension 87 125 adapted to bridge the contact plates 81 and 83 to complete the circuit just described when the train is proceeding at a low rate of speed.

In the operation of my device it will be 130

seen that if the magnet 32' is deenergized the valve 32 closes and hence the air in the chamber 36 may exhaust through the port or vent 33' provided in the lower portion of 5 the valve casing 32 which in turn effects an application of the brakes and an actuation of the throttle lever 41 to cut off the power. It will be noted that whenever the magnet 32', is controlled by the "danger" position 10 of the block signals, it is necessary that the same be reset by hand, since this valve is so constructed that when the armature falls upon demagnetization it drops a considerable distance and cannot be picked up by a 15 mere remagnetization of magnet 32'. When the locomotive passes over the short insulated rail sections 10, which are only a little longer than the insulated truck 65, the circuit from the battery 60, wire 61, coil 32', 20 wire 63 to the locomotive 64, thence through the rails, to the truck 65 and back to the battery, will be broken because the sections 10 are insulated from that portion of the track which is in contact with the other parts 25 of the locomotive. The armature of the valve 32 would become de-energized and allow the valve 32 to fall were not some provision made to energize said magnet 32' in some other way during the passage of the 30 truck 66 over said short insulated section 10.

When, therefore, the locomotive passes through said short insulated rail section 10 and the block ahead is clear, the switches 14 and 16 will both be closed (the switch 14 by 35 the energized magnet 5, the switch 16 by the signal 2 then in "clear" position) in which event a circuit will be established as follows: from battery 18 through wires 19, 20, through short sections 10 to the truck 65, 40 thence through battery 60, wire 61, coil 32', wire 63 to ground 64 on the locomotive, thence through the tracks to bond wires 11, thence by wire 12, contact 13, switch 14, wire 15, switch 16 and wire 17 back to battery 18. In a similar way the circuit for 45 battery 70, when truck 69 is on the insulated rail sections 10, will be battery 70, wire 71, magnet 34', wires 72, 63, to locomotive 64, thence to main rails and to bond wire 11, wire 13, switch 14, wire 15, switch 16, wire 50 26, resistance 27, wires 28, 20, sections 10, truck 69 to battery 70. When therefore the train passes over the short sections 10 and the track ahead is clear, the circuit through 55 the electromagnet 32' will not be broken and the valve 32 will be held in its elevated position. Whenever the signal indicates "danger" the switch 14 will be opened as shown at the beginning of block B, and hence when 60 the truck 65 enters the insulated section of the track, the external circuit to the locomotive, that is, the circuit comprising the wire 12, point 13, switch 14, wire 15, switch 16, point 17, battery 18, wire 19, wire 20, will be 65 broken at the switch 14, and, as above de-

scribed, the circuit carried by the train, that is to say, the circuit battery 18, wire 61, magnet 32', wire 63, locomotive 64 and rails back to truck 65 and thence to battery will also be broken by the insulation between the short 70 rail sections 10 and the adjacent parts of the track. This causes the magnet 32' to become deenergized, thus closing the valve 32 and stopping the train. The distance x is intended to be substantially that necessary in 75 order to stop a train which may be proceeding at a speed not greater than, for instance, thirty miles an hour, before the train can enter the block B from block C since a train in block B may be at the very beginning of the 80 block and if the distance x were not provided, a train in block C might collide with a train in the rear of block B before the automatic apparatus could be effective to stop the train. It will be noted that the train in block C 85 has been referred to as proceeding at a rate of speed not higher than thirty miles an hour and this is because a train in block B, through the signal at the beginning of the block C, caused the actuation of the train 90 controlling mechanism to limit the speed of the train entering block C to a moderate rate in the following manner. When the signal 3 at the beginning of block C is in the "caution" position, the switch 16 in the circuit 95 of battery 18 is open but in contact with the point 25 to throw the resistance 27 into the circuit between the train stopping rail sections 10 of block D and the main rail sections to the locomotive 64. This partial circuit 100 is from the main track section to the bond wires 11, thence by wire 12 to switch 14, thence by wire 15, through switch 16 to contact point 25, wire 26, resistance 27 and wire 28 back to the short insulated section 105 10 and thence through the trucks to the battery and from the battery to the magnet 32 and thence back through the locomotive 64 to the main section of the track. Similarly, when the truck 69 is in the short insulated 110 section 10, the same external circuit comes into play and cooperates with the battery 70 which is in electrical communication with the truck 69. Thus, when the truck 69 passes over this short section, the circuit is as follows: 115 battery 70, wire 71, magnet 34', wire 72, thence by wire 63 to locomotive 64 and to the main tracks, thence through the bond wires 11, wire 12, closed switch 14, wire 15, switch 16 to contact point 25, thence through 120 wires 26, resistance 27, wire 28, short section 10, trucks 69, back to battery 70. It will thus be seen that when the trucks 65 and 69 come one at a time into the rail sections 10 the circuits to each of the electromagnet 125 valves must be by way of this track circuit just described having the resistance 27 thrown in the circuit. Because the magnets 32' and 34' are differently wound so that a smaller current will suffice to cause the mag- 130

net 32' to hold up its armature than will cause the magnet 35' to hold up its armature, the resistance 27 is so proportioned as to so reduce the current supplied to the magnets 5 that the armature of the magnet 32' will be held up while the armature of the magnet 34' will drop when the switch 16 is in engagement with the point 25 which is when the signal 3 is in "caution" position. It will 10 be apparent, therefore, that the valve 32 will be held open when truck 65 enters the sections 10 but the valve 34 will drop to closing position when the truck 69 enters this section. The complete circuit for holding the 15 valve 32 open will be from the battery 60, lead 61, magnet 32', ground lead 63 to the locomotive 64 and therefrom to the bond wires 11, lead 12, switch 14, lead 15, switch 16, point 25, lead 26, resistance 27, lead 28, lead 20, rail section 10, truck 65 to battery 20. The circuit for the electromagnet 34' will be from battery 70, wire 71, magnet 34', lead 72 to wire 63, to locomotive 64, thence to the main track and by bond 11, wire 12, 25 through switch 14, wire 15, switch 16 to wire 26, resistance 27, wire 28 to small insulated track section 10, and thence through the trucks 69 to battery 70. It is to be understood that the batteries 60 and 70 are substantially of the same electromotive power 30 in order that the resistance 27 will effect the deenergizing of magnet 34' but retaining magnet 32' energized in the manner indicated above.

35 As soon as the valve 34 is allowed to close while the valve 32 remains open, it will be seen that the air pressure from the tank 30 will be shut off from the pipe 35 and pass to the cylinder 36 by way of the pipe 45, 40 governor control valve 46 and pipe 48. Thus, if the train in block D is proceeding at a higher rate of speed than, say thirty miles an hour, the arm 56 will be raised out of contact with the valve stem 57 and the 45 air pressure in the central chamber of the casing 47 operates against the upper poppet valve to move the same to open position, the air being vented to the atmosphere through the port 46'. This also causes the lower poppet valve to be moved to its seat, the flow 50 of air from the pipe 45 aiding to close the same and also maintaining it closed. The air in the pipe 48 thus escapes to the atmosphere through the port 46' as well as the 55 port 35' in the valve casing 34 permitting the air pressure in the cylinder 36 and pipe 48 to be decreased to a point where the check valve 50 may drop to open position and the valve 37 opened under the air pressure in 60 the train air pipe 38. This will result in an application of the brakes to the train and cut off the motive power. If, however, the train in block D is proceeding at a lower rate of speed so that the arm 56 is lowered 65 into engagement with the valve stem 57, the

valve 46 is held open and the air pressure is maintained in the cylinder 36 to hold the train pipe valve 37 closed and hence the train may proceed so long as it remains at a moderate rate of speed, but the moment 70 the speed is increased, the valve 46 becomes closed and the brakes are then automatically applied. This prevents the engineer from speeding up the train after entering the block at a "caution" speed. It will be noted 75 that the exhaust valve 50 is held closed by air pressure in the pipe 48 when the valve 46 is open and automatically drops to permit a more rapid exhaust from cylinder 36 when the air pressure is being decreased as above 80 described.

Means are provided whereby the valve 34 is automatically opened by a reenergization of magnet 34' when the train, which has been proceeding as just described under a 85 moderate speed, enters a block whose signal indicates that the block is entirely free and that high speed may be resumed. When such is the case, the switch 14 will be closed on the point 13 and the caution switch 16 90 will be closed to the track battery 18. In this case, when the truck 69 enters the rail sections 10, the track circuit will be through the battery 18 which, together with the train battery 70, immediately reenergizes 95 the magnet 34' raising the armature and opening valve 34. It will be noted, however, that this battery 18 will not automatically open the other valve 32, should it be dropped, because, when the magnet 32' 100 is once deenergized, the armature falls so far down that it must be raised by hand. This would prevent the resuming of speed and the continuing of the train if the magnet 32' were dropped but the train failed 105 to stop before the next block was reached wherein the signal indicated entire clearance.

It will be noted that I have provided 110 means whereby if, seeing a danger signal, the engineer brings the train down to a very low rate of speed before the sections 10 stop the train by causing the danger magnet 32' to be deenergized, which would necessitate stopping the train and the engineer getting out of the cab to reset the magnet 32', he may proceed with his train by himself holding the magnet 32' energized by 115 use of the switch 85 upon condition, and only upon condition, that the train proceed 120 at a very low rate of speed. Thus the engineer may bring his train right up to the rear of a block even though the signal to that block indicates "danger". In this case, the circuit for the magnet 32' is from the 125 battery 60, wire 61 to magnet 32', to wire 63 and thence by wire 86, switch 85, wire 84, plate 83, arm 87, plate 81, wire 80 to truck 65 and thence to battery. In order for the extension 87 of the arm 56 carried by the 130

governor to bridge the contact plates 81 and 83, it is necessary that the train be proceeding at a very low rate of speed, say under four miles an hour. By this mechanism it will be seen that the operation of the trains is greatly facilitated and practically no space of the tracks need at any time be held against traffic excepting in so far as is absolutely necessary in order to 10 prevent collision by the operation of the automatic train controlling mechanism.

In the modification shown in Fig. 2, I have shown a mechanism wherein instead of using the train stopping sections 10, 15 shown in Fig. 1, a ramp 100 is located at any desired position in each block and is adapted to cooperate with a shoe 101 carried by the train to effect an operation of the train stopping and speed controlling 20 mechanism described above in substantially the same manner. The ramp 100 may be located the same distance α from the beginning of the block for the same purpose stated above in regard to the location of 25 the insulated rail sections 10. The track battery 18' is connected to the ramp 100 by lead 20' while a lead 19' passes to the caution switch 16' to lead 15' to the danger switch 14', point 13' and lead 12' to the 30 track rail, as shown. The resistance 27' is connected by a lead 28' to the battery 18' on one end and by a lead 26' to the point 25' at the other side to the caution switch 16'. 35 The two magnets 32'' and 34'' are shown in Fig. 2 as connected to the air supply in the same manner and for the same purpose as that shown in Fig. 1. In Fig. 2, however, a single battery 105 normally supplies the necessary current to energize both magnets 32'' and 34'', and for this purpose a lead 106 connects the battery to a contact plate 107 adapted to be engaged by the shoe 101 while a lead 109 connects the other side of the battery to a lead 110 extending to 40 the magnet 32''. A return lead 111 connects this magnet to the locomotive 64' forming the ground. A lead 112 connects the lead 110 to the magnet 34'' while a lead 113 connects the other side of this magnet 45 to the ground. The contact plate 107 is insulated at 115 from an adjacent contact plate 116 and a lead wire 117 connects this plate 116 to the wire 110.

In the operation of the modification of 50 Fig. 2, it will be seen that the shoe 101 being normally connected to ground in any desired manner as indicated diagrammatically in Fig. 2 by the contact point 101' and wire 101'' connected to the truck 65'. The battery 105 maintains both magnets energized by reason of the ground wires 111 and 113 in a manner that will be readily understood by those skilled in the art. However, when the shoe 101 engages a ramp 100 it is forced 55 away from the contact point 101' breaking

its connection there to the earth and the contact finger on the shoe is raised to engagement with the contact plate 116 thus cutting out battery 105 and throwing the magnets 32'' and 34'' into the circuit of the track 70 battery 18'. The condition of the switches 14' and 16' in Fig. 2 is dependent upon the condition of the adjacent blocks in the same manner in which the danger and caution switches were controlled in the modification 75 of Fig. 1. It will therefore be seen that, in view of the difference in the amount of resistance offered by the magnets 32'' and 34'', the armature of the magnet 32'' will be held up by the track battery 18' even though the 80 resistance 27' be thrown into the circuit, but this resistance 27' will cause the magnet 34'' to be deenergized. It will be evident, of course, that if both the switches 14' and 16' are in contact with the point 13' and the contact of lead wire 19' respectively then both the magnets 32'' and 34'' will be maintained 85 energized, this condition of the track circuit being present when the signal to the block indicates clearance, as is well understood in 90 the art, and as was the case in the modification shown in Fig. 1. It will be further understood that if the danger switch 14' is open, the circuit to both the magnets will be broken and the valves 32 and 34 dropped to 95 closing position, thus effecting an application of the brakes and stopping the train.

In view of the fact that the modification shown in Fig. 2 otherwise operates in substantially the same manner as that fully described above in connection with Fig. 1, a further detailed explanation of the operation of this modified form of construction is deemed unnecessary.

In Fig. 3 I have shown a mechanism which 105 may be utilized in conjunction with the modification illustrated in Fig. 1 whereby, if the insulation for the train stopping rail sections 10 breaks down, the signal in the block in the rear will go to "danger" position and a train approaching such block will 110 be stopped and therefore avoid the possibility of collision which might otherwise result if the train proceeded into the block in which the train stopping sections had become inoperative by reason of a failure of the insulation for the stopping section 10.

The mechanism I have provided for accomplishing these ends consists in means for short circuiting the usual signal track battery in case of a break in the insulation at any one of the sections 10. If the track circuit signal battery is short circuited it is evident that the signal in the preceding block would indicate danger. There has 120 therefore been provided, as shown in Fig. 3, a lead line 150 from one of the sections 10 to a point 151 of the danger switch 152. The other rail section 10 is connected by a lead 125 153, to point 154, to a second danger switch 130

155, both switches 152 and 155 being operated from the usual danger controlling relay 156 for the signal 157. The switches 152 and 155 are respectively connected by leads 158 and 159 to switches 160 and 161 which correspond and are operated by the same position of the signal as the caution switch 16 of Fig. 1. Lead 162 extends from the point 163 of the switch 160 to the track battery 18 which is connected to the bond wire 11, as shown, while the other switch 161 is connected through lead 165 to a resistance 27 and hence by a lead 166 to a lead 167 extending to the bond wire 11 on the other side of the track. The lead 167 has an extension 168 with a point 169 adapted to be engaged by the switch 161 to cut out the resistance 27 for reasons similar to that given in connection with the description of Fig. 1. Furthermore, it will be seen that since both switches 160 and 161 operate in unison, when the switch 161 contacts with point 165, switch 160 is out of contact with point 163, thus cutting off the track battery 18. In this manner it will be evident that the operation of the modification of Fig. 3 is substantially the same as Fig. 1 in so far as operating the train stopping or speed controlling mechanism is concerned, since the track circuits provided in Fig. 3 will make or break the connection between a truck in the train stopping section 10 and a locomotive, for example, or other part of the train in the main track sections in the same manner described above in connection with Fig. 1.

Should the insulation to the sections 10 break down and permit current to pass therethrough, it will be seen that the track battery *a* for that block will be at once short circuited. Thus as soon as the insulation indicated at *h* in Fig. 3, breaks down it will be seen that the battery *a* will then have a metallic circuit through one rail, insulation *h*, section 10, lead 150, switch 152, lead 159, switch 161 to lead 167, either through lead 168 or resistance 27 and lead 166 to the bond wire 11 on the opposite side of the track from the insulation *h*, the circuit being completed by the rail to the battery. The circuit just described requires that the switches 152 and 155 be closed by the relay 156 indicating that the next block is clear and the circuit just described will be made regardless of the position of the caution switch 161. Assuming that the relay 156 is deenergized, as when the signal indicates danger, the relay in the preceding block will have been deenergized by the short circuiting of the battery *a* in the manner just described so that a train in the preceding block has been stopped and cannot proceed so that the position of the switches 152 and 155 now becomes immaterial. Should the insulation *i* break down the short circuit for the battery *a* would then be by way of lead 153,

switch 155, lead 158, switch 160, lead 162, battery 18, bond wire 11 to the other rail of the track and hence to the battery. Should the other insulations *h'* and *i'* break down the circuits will be substantially the same as that just described excepting that the current will be passed through the bond wires 11 around the insulations *h* and *i* to the main track sections, hence through the insulations *h'* and *i'* to the sections 10. In connection with the operation of the modification shown in Fig. 3 whereby provision is made against the breaking down of insulation, it will be noted that when the battery *a* is once short circuited the automatic mechanism operates to stop the train in the preceding block, hence the positions which the various switches 152, 155, 160 and 161 thereafter assume becomes immaterial and before the engineer can proceed with the train which has been stopped, he will eventually locate the difficulty since he will be held up an unreasonable length of time and will therefore know that some unusual reason, such as the breaking down of the insulation of a train stopping section, is the cause of holding his train from proceeding.

Having thus described my invention I claim and desire to protect by Letters Patent of the United States:

1. In an automatic means for controlling the movement of trains in a block system, the combination of a semaphore system whereby the signal of a block is controlled by the condition of the block in advance thereof, a track circuit in each block comprising a switch relay for said block and a track battery located in the block in advance thereof, partial danger and caution circuits comprising danger and caution switches controlled by said track circuit and the semaphore signal in said block, a pneumatic brake applying mechanism, a power cut-off mechanism, a plurality of electro-magnetic valves carried by said train adapted to operate said pneumatic brake applying mechanism and said power cut-off mechanism, speed responsive means comprising a valve and relatively movable contacts, train circuits comprising batteries connected to said electro-magnetic valves and said contacts, said train circuits adapted to be controlled by said danger and caution circuits as a train moves along a block.

2. In a train stopping and speed controlling mechanism, the combination of a pneumatic train stopping mechanism, a plurality of electro-magnetic valves operative to effect an operation of said pneumatic train stopping mechanism, train circuits comprising train batteries connected to said electro-magnetic valves, track circuits comprising switch relays in the controlled blocks and batteries in said blocks and in the blocks in advance thereof, control circuits in each

- block comprising a track battery, a resistance and switches controlled by said relays, said control circuits adapted to selectively operate either of said train circuits for operating either or both of said electro-magnetic valves depending upon the presence or absence of a train in an advance block.
3. In a train stopping and speed controlling mechanism for operating trains in a block system, a brake applying mechanism therefor, a train stopping electromagnetically controlled valve for said mechanism, a speed controlled valve, a second electromagnetically controlled valve adapted to throw said speed controlled valve into or out of connection with said brake applying mechanism, a partial train circuit for each of said electromagnetic valves having a different amount of resistance in each of said circuits, and a coacting track circuit therefor located in each block and controlled by the advance blocks of the system to selectively operate either of said electromagnetic valves dependent upon the condition 25 of the two succeeding blocks in the system.
4. In a train stopping and speed controlling mechanism for operating trains in a block system, the combination of a brake applying mechanism, a train stopping electromagnetic valve controlling said mechanism, a speed responsive valve and a second electromagnetic valve adapted to throw said speed responsive valve into and out of operative connection with said first-mentioned valve, and means located in each block co-operating with said valves to stop a train or throw into action the speed responsive valve depending upon the conditions of the succeeding blocks in the system.
- 40 5. In a train stopping and speed controlling mechanism for operating trains in a block system, the combination of a brake applying mechanism, means comprising a controlling valve carried by the train adapted to effect an operation of the brake applying means, speed responsive means, a pressure controlling valve connected to said first-mentioned controlling valve and coacting means located in each block of the system 45 and connected to the first and second advance blocks relative thereto, means for connecting said coacting means adapted to stop a train if another train is in the next advance block or throw into operation the first-mentioned controlling valve if the first advance block is clear and the second advance block is occupied.
6. In a train stopping and speed controlling mechanism for trains operating in a block system, a brake applying mechanism for a train, an electromagnetically controlled valve adapted, when deenergized, to effect an operation of said brake mechanism, a speed controlled valve therefor, a second 60 electromagnetically controlled valve adapt-
- ed, when deenergized, to throw said speed controlled valve into connection with said brake applying mechanism, a train circuit for each of said electromagnetic valves provided with a different amount of resistance for each of said valves and a coacting partial track circuit provided with resistance means located in each block of the system adapted under certain conditions to throw a resistance into each of the 70 circuits for said electromagnetic valves, whereby the second-mentioned valve will be deenergized and the other valve maintained energized to throw said speed control valve into connection with the brake applying mechanism.
7. In a train stopping and speed controlling mechanism, a plurality of electromagnetic valves adapted to control the action of a train, a normally closed circuit for each 75 of the electromagnets of said valves, one being provided with a different amount of resistance from the other and a partial track circuit provided with resistance means operative when the train is in position to be 80 acted upon by a track circuit provided with said resistance to deenergize one of said electromagnetic valves while the other is maintained energized.
8. In a train stopping and speed controlling mechanism for trains operating in a block system, a partial track circuit in each block of the system adapted to effect an operation of certain train stopping or speed controlling devices carried by a train including a plurality of switches, one of which is controlled by the condition of the first succeeding block and another of which is controlled by the condition of the second 95 succeeding block, a battery in said circuit 100 and a shunt provided with a resistance in said circuit around said battery, the current through both said battery and shunt being controlled by said switches so that if each of the two succeeding blocks be clear 105 the circuit is made through the battery, while if the first succeeding block be occupied, the circuit is completely broken through both said battery and shunt circuits, while if the second succeeding block 110 only is occupied, the circuit will be made through said resistance containing shunt circuit around said battery.
9. In a train stopping and speed controlling mechanism for trains operating in a 115 block system, a partial circuit including a plurality of switches in each block of the system adapted to effect an operation of train stopping or speed controlling devices carried by a train, one of said switches controlled by the condition of the first succeeding block and another of said switches controlled by the condition of the second succeeding block, a battery in said partial circuit and a shunt in said circuit around said 120
- 65 125 130

battery, a resistance in said shunt circuit, the circuits through both said battery and shunt being controlled by said switches so that if each of the two succeeding blocks be 5 clear the circuit is made through the battery, while if the first succeeding block be occupied, the circuit is completely broken through both said battery and shunt circuits, while if the second succeeding block 10 only is occupied, the circuit will be made through said resistance containing shunt circuit around said battery.

10. In a speed controlling mechanism for trains operating in a block system, a brake 15 applying mechanism, a speed controlled valve, an electromagnetically controlled valve, a train circuit for the latter and a partial circuit in each block adapted to affect said train circuit to actuate said electromagnetic valve to throw said speed controlled valve into connection with said brake applying mechanism, and, under other conditions, to actuate said electromagnetic valve to throw said speed controlled valve 20 out of operative connection with said brake applying mechanism.

11. In a speed controlling mechanism for trains operating in a block system comprising automatically operated block signals, a 30 pneumatic brake applying mechanism, an electro-magnetically controlled valve connected to said brake applying mechanism and adapted when energized to maintain said brake applying mechanism inoperative 35 and when de-energized to cause an operation of said brake applying mechanism, a speed controlled valve pneumatically connected to said brake applying mechanism and said electro-magnetically controlled 40 valve, train circuits for normally energizing said electro-magnetically controlled valve, partial circuits in each block, a track circuit in each block, the condition of said partial circuits controlled by the said track 45 circuit and said block signals dependent upon the presence or absence of a train in the adjacent and advance blocks, said partial circuits affecting said train circuits to effect a de-energization of said electro-magnetically controlled valves when a train is 50 present in the advance block, said speed control valve operative at a predetermined rate of speed of travel of a train to effect an operation of said brake applying mechanism and at other speeds to maintain said 55 brake applying mechanism inoperative independent of said electro-magnetically controlled valves.

12. In a speed controlling mechanism for 60 trains operating in a block system, the combination of a pneumatic brake applying mechanism, an electromagnetically controlled valve connected to said brake-applying mechanism and adapted to throw the same 65 into and out of operation, a speed respon-

sive mechanism connected to said brake applying mechanism and adapted to effect an operation thereof, a normally closed train circuit for said electro-magnetically controlled valve, a partial track circuit located 70 in each block adapted to be interposed in said normally closed train circuit and means in said partial circuit controlled by the condition of the advance blocks in the system so as to deenergize said electromagnetically 75 controlled valve when in one position and to automatically reenergize the same when in another position.

13. In a train stopping mechanism the combination of a pneumatic brake-applying 80 mechanism, an electromagnetically controlled valve connected thereto and adapted when de-energized to effect an operation thereof, a speed controlled valve connected to said brake applying mechanism, a second 85 electromagnetically controlled valve connected to said brake applying mechanism and said speed controlled valve, a train circuit for each of said electromagnetic valves, a partial track circuit located in each block 90 of a block system adapted to be thrown into electrical connection with said train circuits and means in said partial track circuit for selectively controlling each of said train 95 circuits dependent upon the condition of the two succeeding blocks of the block system to actuate one of said valves to stop a train or actuate the other valve to permit the same to proceed at a reduced rate of 100 speed.

14. In a train stopping mechanism the combination of a pneumatic brake applying mechanism, an electromagnetically controlled valve connected thereto and adapted 105 to effect an operation thereof, a speed controlled valve connected to said brake applying mechanism, a second electromagnetically controlled valve connected to said brake applying mechanism and said speed controlled valve, a train circuit for each of 110 said electromagnetic valves, a partial track circuit located in each block of a block system adapted to be thrown into electrical connection with said train circuits and means in said partial track circuit for selectively controlling each of said train 115 circuits dependent upon the condition of the two succeeding blocks of the block system to actuate one of said valves to stop a train or actuate the other valve to permit the 120 same to proceed at a reduced rate of speed, said partial track circuit being located at such a distance in the rear of a block as to insure the stopping of a train before reaching the next block when the train is proceeding at the reduced rate of speed.

15. In a train stopping and speed controlling mechanism including a set of insulated rail sections in each block of a block system, the combination thereof with a train control 130

- ling track circuit connected to each set of insulated sections, a block relay and battery therefor, means to short circuit the said relay battery in a block if the insulation of 5 said rail sections breaks down, comprising a track circuit having a set of lead wires extending from each of the insulated rail sections to the main rail sections on the opposite side of the track outside of said insulated 10 sections, whereby if the insulation on either partial track and at either end of the insulated section fails, the circuit from the relay track battery will pass through said track circuit across from one rail of the track to the other and short circuit said battery.
- 15 16. In a train stopping and speed controlling mechanism for trains operating in a block system, the combination of a pneumatic train stopping mechanism, a plurality of 20 electromagnetic valves and a governor controlled valve adapted to be interposed in said mechanism, one of said electromagnetic valves adapted to actuate said train stopping mechanism to stop a train and another of 25 said electromagnetic valves adapted to interpose said governor controlled valve in said train stopping mechanism, a train circuit for each of said electromagnetic valves, a track circuit in each block adapted to control the 30 actuation of said electromagnetic valves, said track circuit including a set of insulated rail sections in each block of a block system, a train controlling track circuit connected to each set of insulated sections, a block relay 35 and battery therefor, means to short circuit the said relay battery in a block if the insulation of said rail sections breaks down,
- comprising, as a part of said track circuit, a set of lead wires extending from each of the insulated rail sections to the main rail 40 sections on the opposite side of the track outside of said insulated sections, whereby if the insulation on either track and at either end of the insulated section fails, the circuit from the relay track battery will pass through 45 said track circuit across from one rail of the track to the other and short circuit said battery.
17. In a train stopping and speed controlling mechanism for trains operating in a 50 block system, the combination of a pneumatic train stopping mechanism, a plurality of electromagnetic valves and a governor controlled valve adapted to be interposed in said mechanism, one of said electromagnetic 55 valves adapted to actuate said train stopping mechanism to stop a train and another of said electromagnetic valves adapted to interpose said governor controlled valve in said train stopping mechanism, a train circuit for 60 each of said electromagnetic valves, a partial track circuit in each block controlled by the succeeding blocks of the system and adapted to be thrown into connection with said train circuit to selectively operate either of said 65 electromagnetic valves, depending upon whether a train is in the next succeeding block or whether that block is clear but a train is in the second succeeding block.

In witness whereof, I have hereunto set 70 my hand this 21st day of September, A. D. 1917.

FRANK C. WILLIAMS.
